(57) **CLAIM**

The ornamental design for an air cleaner housing, as shown and described.

DESCRIPTION

FIG. 1 is a front perspective view of a first embodiment of an air cleaner housing according to the invention;

FIG. 2 is a rear perspective view of the air cleaner housing of FIG. 1;

FIG. 3 is a front view of the air cleaner housing of FIG. 1; FIG. 4 is a right side view of the air cleaner housing of FIG. 1, the left side view being a mirror image;

FIG. 5 is a rear view of the air cleaner housing of FIG. 1; and,

FIG. 6 is a top view of the air cleaner housing of FIG. 1. The broken line showing is for illustrative purposes only and forms no part of the claimed design.
